UNITED STATES PATENT OFFICE.

JAMES E. NISBET, OF JACKSONVILLE, ALABAMA.

LOCK.

1,176,594.

Specification of Letters Patent. Patented Mar. 21, 1916.

Application filed December 7, 1914. Serial No. 875,912.

To all whom it may concern:

Be it known that I, JAMES E. NISBET, a citizen of the United States, residing at Jacksonville, in the county of Calhoun and State of Alabama, have invented certain new and useful Improvements in Locks; and I do hereby declare the following to be a full, clear, and exact description of the invention, such as will enable others skilled in the art to which it appertains to make and use the same.

This invention relates to new and useful improvements in locks, and the object of the invention is to provide a lock having a sliding latch bar adapted to be operated by a knob, and a novel type of locking means for the latch bar by means of which the latch bar can be locked against movement when in an operative position, the said locking means being capable of being operated at a point distant from the door.

Other objects will appear and be better understood from that embodiment of my invention of which the following is a specification, reference being had to the accompanying drawing forming a part thereof, in which:

Figure 1 is a perspective view of a door showing this improved lock applied thereto, Fig. 2 is a vertical sectional view of a lock constructed in accordance with this invention, Fig. 3 is a sectional view taken on line 3-3 of Fig. 2, Fig. 4 is an enlarged detail fragmentary view in elevation of the interior of the lock showing the same in its locked position, and Fig. 5 is a view similar to Fig. 4 showing the device in its unlocked position.

Referring now to the drawings by characters of reference, the numeral 1 designates the building of the ordinary construction which is provided with the usual door frame 2 in which the door 3 is hinged. This building is provided with a porch 4 which is covered by the roof 5 and the door carries a suitable lock designated generally by the numeral 6. This lock 6 comprises the casing 7 in which the usual latch 8 is slidable. This latch is controlled by a latch-operating lever 9 which in turn is operated from the shaft 10, on which the knob 11 is secured, and the latch as in ordinary cases is provided with the button-locking mechanism 12 as is clearly shown in Fig. 2.

My improved lock, which is designated generally by the numeral 13, comprises the

rectangular body 14 which is cast on the interior of the casing and provided with an internally screw threaded recess 15 in which the screw 16 extends. This screw 16 projects through the aperture 17 formed in the arcuate spring plate 18, which plate is designed to bear against the locking member 19 which is provided with the elongated, rectangular aperture 20, which aperture is of sufficient size to receive the rectangular lug or boss 14 hereinbefore referred to. Secured to opposite ends of the body 19 as at 21 are the locking and unlocking cords 22 and 23 respectively, which pass through suitable apertures 24 formed in the casing 7 as clearly shown in the drawings. The operating cords 22 and 23 slidably extend through eye bolts 22' and 23' mounted, respectively, on the upper side of the door jamb and the lower end of the door, as shown in Fig. 1 of the drawing. The operating or locking cords 22 and 23 are of sufficient length to admit of the door being fully opened, and also to admit of the free ends of the cords being positioned at points distant from the door.

From the foregoing it will be apparent that when it is desired to lock the door, the same is closed in the usual manner which will cause the latch to press backwardly against the action of the usual spring and after the door has been closed the flexible connection 22 is pulled, which will cause the locking element 19 to slide upwardly on the boss 14 and in rear and in close proximity to the lever 9, so as to prevent operation of the lever and due to the spring action of the arcuate plate 18, it will be apparent that the locking element will be held against accidental movement. The end of the flexible connection may be carried to any point and hidden in any desired manner around to the side or rear of the building or any other point desired by the user. When the unlocking cord 23 is operated the locking member 19 will be withdrawn from behind the lever and returned to normal position, admitting of the operation of the lever by turning the shaft 10. The unlocking cord 23 may be carried to a point distant from the terminal of the locking cord, and it will thus be evident that the concealing of the locking cord may have nothing to do with the concealing of the unlocking cord, thus rendering the lock exceedingly safe. It is to be understood that the person using this device may hide the terminals of the

cords 22 or 23 at any desired point or points so as to baffle any attempt at unlocking the door by unauthorized persons. In this way it will be evident that a particularly simple and efficient device is provided which may be easily and cheaply constructed and will effectively prevent the latch of the door from being unlocked by unauthorized persons.

10 While in the foregoing there has been shown and described the preferred embodiment of this invention, it is to be understood that such changes may be made in the combination and arrangement of parts as 15 will fall within the spirit and scope of the invention as defined in the appended claim.

What is claimed is:—

20 In a lock, the combination with a casing having a sliding latch bar therein and a lever having operative connection with the latch bar, of a lug formed integrally with the inner surface of one wall of the casing and disposed below the latch bar and the 25 lever, a rectangular shaped body located within the casing and having an elongated

opening therein for slidably receiving the lug, a locking cord having one end extending into the casing and connected to one end of the slidable body and adapted when pulled in one direction to cause the slidable body to move upwardly and in rear of and in close proximity to the lever, so as to prevent 30 operation of the lever, an unlocking cord having one end extending into the casing and having connection with the opposite 35 end of the slidable body and adapted, when operated, to move the slidable body below the lever, and a spring plate frictionally engaging the outer side of the slidable body for holding the body against movement 40 when the latter is moved to operative position, and means for regulating the frictional engagement between the plate and the slidable body.

In testimony whereof I affix my signature 45 in presence of two witnesses.

JAMES E. NISBET.
